(57) **CLAIM**

The ornamental design for a visor mountable display, as
shown and described.

DESCRIPTION

FIG. 1 is a front perspective view, viewed from the right side
and top, showing the new design of the visor mountable
display employing adjustable straps for mounting.

FIG. 2 is a front perspective view, viewed from the left side
and bottom, of the visor mountable display of FIG. 1.

FIG. 3 is a rear perspective view of the visor mountable
display of FIG. 1.

FIG. 4 is a front view of the visor mountable display of FIG.
1.

FIG. 5 is a rear view of the visor mountable display of FIG.
1.

FIG. 6 is a top view of the visor mountable display of FIG.
1.

FIG. 7 is a bottom view of the visor mountable display of
FIG. 1.

FIG. 8 is a left side view of the visor mountable display of
FIG. 1; and,

FIG. 9 is a right side view of the visor mountable display of
FIG. 1.

The broken line showing of a USB port is for the purpose of
illustrating portions of the visor mountable display that
forms no part of the claimed design.

1 Claim, 5 Drawing Sheets
